F. MANKEY.

MOLDING.

No. 16,457.

Patented Jan. 12, 1886.

UNITED STATES PATENT OFFICE.

FREDERICK MANKEY, OF WILLIAMSPORT, PENNSYLVANIA.

DESIGN FOR A MOLDING.

SPECIFICATION forming part of Design No. 16,457, dated January 12, 1886

Application filed November 13, 1885. Serial No. 182,757. Term of patent 7 years.

To all whom it may concern:

Be it known that I, FREDERICK MANKEY, of Williamsport, Lycoming county, Pennsylvania, have invented and produced a new and original Design for Moldings, of which the following is a specification, reference being had to the accompanying photograph, forming part hereof.

The outline of one edge of the molding 10 shows a series of scallops, A B, the scallops B being smaller and of greater curvature than the scallops A. The scallops B also project beyond the scallops A, and the said scallops B and A alternate. The opposite edge of the 15 molding has at regular intervals indentations, depressions, or concavities C, the said concavities being directly opposite the scallops A. The said edge between the concavities C is straight. On the face of the molding, and diverging 20 from a point at about the middle of a straight

portion of said edge, are curved grooves or channels D. Said grooves extend from the point of divergence to the points of intersection or meeting of a scallop B with its adjacent scallops A A. These pairs of diverging 25 grooves are repeated at intervals on the face of the molding. In about the middle of each scallop B is a circular depression, E.

I claim—

The design for a molding, substantially as 30 herein shown and described, which consists in the alternating scallops A B on one edge, the concavities C and intermediate straight portions on the opposite edge, and the curved grooves D on the face of the molding.

FREDERICK MANKEY.
